UNITED STATES PATENT OFFICE.

JOHN F. FARRINGTON, OF NEW YORK, N. Y., ASSIGNOR TO WESTERN ELECTRIC COMPANY, INCORPORATED, OF NEW YORK, N. Y., A CORPORATION OF NEW YORK.

WAVE MODULATING.

Application filed July 31, 1920. Serial No. 400,363.

- This invention relates to modulating systems and circuits for use in signaling or other wave transmission systems, and, more particularly, in telephone systems.
- 5 An object of the invention is to provide improvements in systems and methods of modulation dependent upon the principle of variable absorption of the high frequency energy.
- 10 The herein described systems embodying the invention comprise space discharged oscillators having a suitable current supply circuit, an input circuit connected to a cathode and the grid or other equivalent element of the device, and an output circuit connected to the cathode and the anode. In shunt to the output circuit is the primary of a high frequency transformer whose secondary is connected to a variable impedance modulating device of any suitable type, but preferably, a discharge tube having its input circuit controlled by the source of waves or signals, in accordance with which the modulation is to be effected. This 15 type of modulator acts to cause variable generation of waves by the oscillator. The absorption device causes a large effect since at those instances when maximum high frequency energy is being absorbed in the modulator, minimum high frequency energy is being supplied to the grid circuit of the oscillator, and vice versa. But certain principles of the invention may be applied in systems in which there is substituted for the oscillator, a device having a separate source of high frequency waves applied to the input circuit thereof.
- 20 The aims and objects of the invention will be more thoroughly understood by references 40 to the following description and the appended claims. In the accompanying drawing Figs. 1 and 2 represent the application of the invention in systems employing different forms of oscillators, while Fig. 3 represents an auto-transformer which may be substituted for the transformer 9, 10 of Figs. 1 and 2.
- 25 In Fig. 1 a tube or system of tubes 1 of the ordinary type comprising a heated filamentary cathode, and anode and an impedance controlling grid contained in a highly evacuated vessel, is connected to an antenna circuit 2 for the generation of oscillations therein. The high frequency output circuit 30 between the anode and the cathode is connected across the radiating capacity of the antenna circuit. The input circuit between the cathode and the grid is connected across the capacity 3. For convenience of adjustment it may be also connected across a small portion of the inductance of the antenna circuit. A suitable source 4 supplies space current between the anode and the cathode. If the source 4 is of material impedance to waves of the frequency to be generated by the oscillator, a capacity 5 may be provided to furnish a low impedance path there-around. The tuning of the antenna may be varied in any convenient manner to change the frequency of the waves produced. Auxiliary elements of the oscillator which aid in producing efficient operation, are a condenser 6 in the grid circuit and a high resistance leak path 7 connected between the grid and the filament. As so far described, the system is incapable of generating oscillations since the circuit 8 through the source 4 would constitute a short circuit upon the output circuit of the oscillator if no impedance elements were connected therein. This 35 is prevented from acting as a short circuit, by including the primary 9 of a transformer therein. The secondary 10 of the transformer is included in the plate circuit of a variable impedance tube 11, which is controlled by a source of speech or other signal waves, such as microphone circuit 12 connected to the input circuit 13 thereof. If the secondary 10 were removed from the system, primary 9 would act as a choke coil 40 to prevent the passage of high frequency waves through circuit 8. The same result will occur if the secondary 10 is included in a circuit of very high impedance. In 45 practice, however, the impedance of the circuit including the secondary 10 is adjusted by varying the batteries 14 and 15 so that the amount of energy absorbed in the device 11 will bring the waves generated by the device 1 to the desired average value. The sound frequency waves acting in the microphone circuit 12 will cause the impedance of the device 11 to vary, thereby varying the energy transferred from the primary 9 to the secondary 10, and causing corresponding 50 variations in the high frequency waves produced in and radiated from the antenna circuit 2.

The transformer 9, 10 is preferably, in the case of radio systems, designed to efficiently transfer energy corresponding in frequency to that desired to be radiated. The coupling between the primary and the secondary may be made variable in any convenient manner. A tight coupling with small capacity between the primary and secondary is usually desirable. While magnetic material may be used for the case of this transformer in some instances it should be clearly understood that, in accordance with this invention, the transformer is always designed to transfer carrier or high frequency energy and not to transfer speech or low frequency energy. The batteries 14 and 15 are not essential and either one or both of them may be omitted from the system but less distortion and greater ease of adjustment is realized when they are included.

In Fig. 2, a different form of oscillator is illustrated in which the antenna circuit 2 is insulated from the remainder of the system. The antenna circuit in this system likewise primarily determines the frequency of the generated oscillations which may be varied by varying the constants thereof. The transfer of high frequency energy to the antenna is accomplished through the coupling between the coils 16 and 17. The antenna circuit is connected back to the grid circuit of the tube through the coupling between the coils 18 and 19. A variable condenser 20 is connected in shunt to the coil 16. This condenser is made variable, not primarily for the purpose of varying the generated frequency, but for the purpose of changing the effective coupling of the anode-cathode circuit of the tube to the antenna and also for the purpose of preventing the occurrence of parasitic oscillations of undesired frequency in the system. The condenser 6 and resistance 7, while differently located, function in a manner similar to the correspondingly numbered elements in Figure 1. In series with the source 4 is placed an inductance coil 21 so designed as to prevent the passage of current variations of speech frequency. Condenser 5 serves to by-pass high frequency variations around the coil 21, although the distributed capacity of the coil 21 may be sufficient to render this by-pass unnecessary. The transformer primary 9 is connected in shunt to the capacity 20 and is associated with the secondary 10 and the elements 11, 12, 13, 14 and 15 in the same manner as described in connection with Figure 1.

In Figure 3 is illustrated an auto-transformer in which the windings 9 and 10 are consolidated. This may be substituted for that shown in the other figures.

In the operation of the systems described, high frequency waves produced in the antenna circuit 2 will be caused to vary in

amplitude in accordance with speech frequency variations in the circuit 12. If the wave length, the couplings of the oscillator with the antenna circuit, the constants of the modulating tube 11, and the transformer 9, 10 are properly adjusted for efficient operation, then without change of the modulator 11 or the transformer 9, 10, the system will work efficiently over a considerable range of adjustment of the oscillator and of the antenna for changing the wave length, or over a considerable range of variation of antenna constants, the wave length remaining fixed. Furthermore, it is not necessary, if the transformer 9, 10, be suitably designed and adjusted that the impedance of the modulating tube 11 be extremely low. It is not convenient to provide tubes which will be of extremely low impedance without impressing a high positive potential upon the grid which would tend to cause distortion. Large amounts of power can therefore, by the use of transformers, be controlled without making the grid of the tube 11 excessively positive with respect to the cathode or without making it at all positive if a suitable negative grid battery 14 is used. Large amounts of power can be varied by a variable impedance of comparatively small power capacity.

In applying the invention to transmission over conductor lines a suitable closed non-radiating circuit may be substituted for the antenna circuit 2 and a transmission line connected thereto in any desired manner. Variations of line or antenna constants in this case will not cause variations in carrier frequency. The carrier waves generated, while referred to as high frequency waves, may in the case of line transmission, be of a comparatively low frequency. This is particularly the case where the modulating waves are of relatively low frequency with respect to the essential frequencies of sound waves of speech. In any case the transformer 9, 10 will be modified to handle efficiently energy of the frequency or frequencies to be transmitted. It should be understood, however, that while the invention is applicable to other systems, it is more particularly designed for and usable in radio systems.

The novel features inherent in the invention are defined in the appended claims.

What is claimed is:

1. A modulating system comprising an electron discharge device, appropriate circuits connected thereto whereby said device functions as a generator of carrier waves, said circuits including a grid-cathode circuit and an external anode-cathode circuit having a portion independent of said grid-cathode circuit, and a modulating device including means for variably absorbing carrier wave frequency energy connected in

effective shunt to said independent portion of the external anode-cathode circuit.

2. A modulating system comprising an electron discharge device, appropriate circuits connected thereto whereby said device functions as a generator of carrier waves, said circuits including a grid-filament path and an anode-cathode path in addition to said grid-filament path, a modulating device including means for variably absorbing carrier frequency energy connected in high frequency energy shunt relation to said anode-cathode path, and means for varying the impedance of said device in accordance with signals.

3. A modulating system comprises a space discharge device, appropriate circuits connected thereto whereby said device functions as a generator of carrier waves, said circuits including a cathode-anode circuit having a cathode-anode path within said device, a primary winding of a transformer adapted to transfer carrier wave frequency energy connected across cathode-anode path, and a device variably absorptive of carrier wave energy in circuit with the secondary winding of said transformer.

4. A modulating system comprising a space discharge device, appropriate circuits connected thereto whereby said device functions as a generator of carrier waves, said circuits including a carrier wave output circuit, a transformer adapted to transfer carrier wave energy, the primary of said transformer being connected in shunt to a portion of said carrier wave output circuit, and a modulating device variably absorptive of carrier wave energy connected in circuit with the secondary of said transformer.

5. A modulating system comprising an electron discharge device, appropriate circuits connected thereto whereby said device functions as a generator of high frequency oscillations, said circuits including a high frequency output circuit, a primary winding of a transformer adapted to transfer high frequency wave energy, connected in shunt to at least a portion of said output circuit, a space discharge tube in circuit with the secondary winding of said transformer, and means for varying the impedance of said tube in accordance with sound waves.

6. A modulating system comprising an

electron discharge device, an input circuit for said device for receiving high frequency waves to be applied thereto, an output circuit for said device, a high frequency transformer having its primary winding connected across a portion of said output circuit, and a modulating discharge device of variable impedance to high frequency waves for variably absorbing the energy of such waves connected across the secondary winding of said transformer.

7. A modulating system comprising a space discharge device connected with appropriate circuits for the generation of high frequency oscillations, an output circuit for said device, a primary of a transformer adapted to transfer high frequency energy in shunt to said output circuit, and a modulating vacuum tube variably absorptive of high frequency energy included in circuit with the secondary of said transformer.

8. A modulating system comprising a space discharge device, appropriate circuit arrangement connected thereto whereby said device functions as a generator of oscillations of carrier frequency, said circuits including an input circuit and an output circuit, a transformer adapted for the efficient transfer of carrier frequency energy having its primary connected in shunt to one of said circuits, and a discharge device of variable impedance to high frequency energy connected in circuit with secondary of said transformer.

9. A modulating system comprising a space discharge device, circuit arrangements connected thereto for the generation of carrier oscillations, an output circuit for said device, a modulating device of variable impedance to the carrier oscillations, and means including a transformer efficient for carrier wave frequencies connecting said modulating device to said output circuit whereby the carrier frequency potential difference applied to said modulating device bears a substantially constant relation to the carrier frequency potential difference across said output circuit irrespective of the adjustment of said circuit arrangements.

In witness whereof, I hereunto subscribe my name this 27th day of July, A. D. 1920.

JOHN F. FARRINGTON.
